UNITED STATES PATENT OFFICE.

JOSEPH W. SHIPLEY, OF HYATTSVILLE, MARYLAND.

RAILROAD-TIE.

1,004,483.

Specification of Letters Patent. Patented Sept. 26, 1911.

Application filed December 9, 1910. Serial No. 596,528.

To all whom it may concern:

Be it known that I, JOSEPH W. SHIPLEY, a citizen of the United States, residing at Hyattsville, in the county of Prince George 5 and State of Maryland, have invented certain new and useful Improvements in Railroad-Ties, of which the following is a specification, reference being had therein to the accompanying drawing.

10 This invention relates to railway ties and track fastenings therefor, and the principal objects of the same are to provide a reinforced plastic tie that is formed of material that will quickly harden and is shaped so 15 that it will have a firm engagement with the roadbed without danger of sinking therein; to provide novel means that will prevent the ties creeping; and to provide novel track fastening means that will normally 20 retain the rails in rigid relation to the tie but which can be readily released when necessary to permit removal of the rails.

In carrying out the objects of the invention generally stated above, it will be understood, of course, that the essential features 25 of the same are necessarily susceptible of changes in details and structural arrangements, preferred and practical embodiments of which are shown in the accompanying 30 drawings, wherein:—

Figure 1 is a top plan view of the improved tie and track fasteners, shown in use. Fig. 2 is a vertical longitudinal sectional view taken on the line 2—2, Fig. 1. Fig. 3 35 is a detail perspective view of the base plate of the tie. Fig. 4 is a similar view of one of the rail seats. Fig. 5 is a perspective view of one of the rail clamps. Fig. 6 is a transverse vertical sectional view showing a modified type of rail clamp. Fig. 7 is a detail 40 inverted perspective view of the clamp shown in Fig. 6.

Referring to the accompanying drawings by numerals, it will be seen that the improved tie comprises a plastic body 8 that is 45 preferably formed of a mixture of crushed stone, sand and cement which in the process of molding has the arched tie rods 9 longitudinally embedded therein in crossing relation, said rods being transversely corrugated 50 so that they will have a firm engagement with said body.

The bars 9 are formed of elongated flat material, the corrugations of which extend 55 transversely and said bars are arched at their centers. The said bars extend substan-

tially the entire longitudinal length of the ties, and are arranged so that ends of adjacent bars diverge and the centers thereof project in opposite directions. For example in Fig. 2, two of the bars are shown, one bar having its ends at the upper portion of the ends of the tie and its arched center at the center of the bottom portion of the tie. The other bar has its ends at the lower portion of the ends of the tie, and its arched center at the upper portion of the center of the tie. This arrangement of bars reinforces the body at all portions.

Externally the sides and ends of the tie 70 are provided with the upper and lower beveled surfaces 10 which impart an ornamental appearance to the tie and also provide the outwardly projecting portions which tend to prevent the ties unduly sinking in the roadbed. The base of the tie is provided with a longitudinal recess 11 in which a flat plate 12 is seated, said plate having its ends provided with spaced bolt openings 13 and its central portion provided with a longitudinally extending depending flat wing 14 that decreases in size from its central portion and its ends merge into the bottom of plate 12. Said wing 14 projects well below the bottom or base of the tie and enters the roadbed so 85 that it will prevent the tie creeping.

The top surface of the tie is provided with longitudinal recesses 15 adjacent each end which are intersected by the transverse grooves 16 which extend entirely across the 90 top surface of the tie. Supporting plates 17 are snugly fitted in recesses 15 and provided with centrally depressed portions which snugly fit the grooves 16 and form seats 18 in which the base flanges of the rails are 95 seated. The supporting plates 17 have openings 20 formed through them which are in alignment with the end openings of the base plate 12 and substantially U-shaped bolts 21 are passed through the end openings of 100 plate 12, through the tie, and the end openings 20 of the plates 17.

Clamping plates 22 are detachably fastened to the plates 17 by means of the bolts 21 which pass through central openings 23 of said plates 17 and the lock nuts 24. Said clamping plates 22, as shown in Figs. 1, 2 and 3, are rectangular in shape and have their ends rounded and down-turned to provide the pendent flanges 25 110 which rest on the plates 17 and the pendent flanges 26 which are beveled to conform to

and rest on the top surfaces of the flanges of the rails 19.

It will be clear from the foregoing that by tightening the nuts 24, the plates 22 will firmly clamp the rails 19 to the tie, and that by releasing said nuts, said rails can be readily removed. It will also be seen that the described shape of the tie will permit the same to be partly embedded in the roadbed without danger of the same sinking farther, and that the arched corrugated rods or bars add great strength to the tie.

Another distinctive feature of the invention is in the employment of the base plates 12 equipped with the wing 14 by means of which simple means are provided for preventing the tie creeping and at the same time providing a bearing plate for the bolts 21.

20 In Figs. 6 and 7, a modification of the clamping plate is suggested in which the clamping plates are in the form of cup shaped disks 27 having central openings 28 through which the bolts 21 pass. The pendant annular flanges 29 of said disks rest on the plates 17 and have the beveled lips 30 that engage the base flanges of the rails 19. With the exception of the clamps, this form of the invention is the same as that 30 described in connection with Figs. 1, 2, 3 and 4.

What I claim as my invention is:—

1. A tie formed of plastic material having the outer surfaces of its ends and sides 35 provided with upper and lower beveled portions arranged to provide an outstanding centrally located surrounding projection to prevent the tie unduly sinking in the roadbed, reinforcing means embedded in said 40 tie, and rail fastening means carried by said tie.

2. A plastic tie having a centrally located longitudinally extending base recess, the upper surface of said tie provided with 45 longitudinal recesses adjacent each end and transverse grooves that intersect said upper recesses, a base plate seated in the base recess and provided with roadbed engaging means, supporting plates seated in the upper recesses and having central rail seats that rest in said grooves, rail clamps resting on said upper plates, bolts extending through the base plate, tie, upper plates and clamps, and nuts engaging said bolts for 50 locking said clamps in rail-engaging positions.

3. A plastic tie having a base recess and an upper recess adjacent each end, said upper recesses being intersected by trans-

verse grooves, supporting plates seated in 60 said upper recesses and having rail seats that lie in said grooves, anti-creeping means seated in said base recess, bolts for rigidly connecting said anti-creeping means and supporting plates, rail clamps carried by 65 said bolt, and lock nuts for adjusting said clamps.

4. A railway tie comprising a body, longitudinally arranged anti-creeping means carried by the bottom thereof, supporting 70 plates on said tie and provided with rail seats, rectangular-shaped clamping plates having a pending flange at one end for contacting with said plates and a beveled pendant flange at the other end for engaging a 75 rail flange, and common means for locking said supporting plates and clamping plates to said tie.

5. A railway tie comprising a body, anti-creeping means on the bottom thereof, rail 80 supporting plates on the top of said tie, rail clamps carried by said plates, and common means for detachably locking said anti-creeping means, supporting plates, and clamps to said tie.

6. A railway tie comprising a body, supporting plates adjacent each end of the upper surface thereof and provided with centrally depressed transverse rail seats, rail clamps seated on the ends of said plates, 90 anti-creeping means carried by said body and common means for detachably locking said plates, anti-creeping means and clamps to said body.

7. A tie comprising a plastic body, reinforcing means embedded in said body, a vertically arranged pendent anti-creeping wing centrally located on and extending longitudinally of the bottom of said body, rail engaging means carried by the top of 100 said body, and means for fastening said rail-engaging means and anti-creeping wing to said body.

8. A tie comprising a body, rail-engaging means carried thereby, a plate arranged 105 longitudinally of the bottom of said body, and a longitudinally extending centrally located wing depending from said plate, said wing tapering in depth from its center to its ends and said ends merging into said 110 plate.

In testimony whereof I hereunto affix my signature in presence of two witnesses.

JOSEPH W. SHIPLEY.
